UNITED STATES PATENT OFFICE

157,318

GRILLE GUARD

Lilburn Martin Dick Bailey, Memphis, Tenn.

Application December 3, 1948, Serial No. 149,961

Term of patent 14 years

(Cl. D14—6)

To all whom it may concern:

Be it known that I, Lilburn Martin Dick Bailey, a citizen of the United States of America, residing at Memphis, in the county of Shelby and State of Tennessee, have invented a new, original, and ornamental Design for Grille Guard, of which the following is a specification, reference being had to the accompanying drawings, forming part thereof.

In the drawings:

Fig. 1 is a perspective front view of a grille guard showing my new design.

Fig. 2 is a top plan view.

I claim:

The ornamental design for a grille guard, substantially as shown.

LILBURN MARTIN DICK BAILEY.
